VALVE FOR DELIVERING CARBONATED BEVERAGES

Norman L. Luster, Chicago, Ill.

Application April 19, 1946, Serial No. 663,299

7 Claims. (Cl. 137—505)

1

This invention relates to improvements in valves for delivering carbonated beverages.

It has heretofore been known that the gas in solution in a carbonated liquid is retained when the carbonated liquid is delivered in the form of a thin circular sheet flowing from a region of high pressure to a region of lower pressure. It has been found, however, that this sheet of water must be extremely thin in order to produce the desired result when used with the conventional beverage dispensing equipment. In order that this sheet be thin, the carbonated liquid has been directed onto a disk closely adjacent a fixed surface or another disk, which forms the liquid into a thin circular sheet. Since the space through which the liquid passes is extremely thin in order to form the liquid into a thin film, sediment in the carbonated liquid clogs the orifice through which the liquid passes.

The principal objects of my invention are to overcome these difficulties and prevent the clogging of the orifice through which the carbonated liquid passes with sediment, by providing a valve for delivering carbonated liquids in the form of a thin film, which valve has a variable constriction which opens wide and remains in a wide open position when the flow of carbonated fluid through the valve stops, and automatically narrows to a predetermined setting when a carbonated liquid flows through the valve.

A more specific object of my invention is to provide a substantially constant flow delivery valve operated by the action of a carbonated liquid and adapted to be attached to a conventional type of soda fountain draft arm, which restricts the delivery orifice of the valve and causes the carbonated liquid to be delivered in a thin film when the draft arm valve is turned on to admit liquid to the delivery valve, and which opens wide when the flow of carbonated liquid stops, to permit the orifice to clear itself of sediment.

A still further object of my invention is to provide a constant flow valve for delivering carbonated liquids which includes a substantially balanced double valve operated by the carbonated liquid, to close and provide predetermined restricted passageways when the carbonated liquid flows into said valve and to open wide to permit the valve to clear itself when the flow of the carbonated liquid stops.

These and other objects of my invention will appear from time to time as the following specification proceeds and with reference to the accompanying drawings wherein:

Figure 1 shows a valve constructed in accordance with my invention attached to a soda fountain draft arm of a conventional type;

Figure 2 is an enlarged sectional view taken through the valve shown in Figure 1;

2

Figure 3 is a fragmentary sectional view taken substantially along line 3—3 of Figure 2;

Figure 4 is a fragmentary transverse sectional view taken substantially along line 4—4 of Figure 3;

Figure 5 is a view showing a modified form of valve constructed in accordance with my invention;

Figure 6 is a sectional view of a valve illustrating another modified form of my invention;

Figure 7 is a sectional view taken substantially along line 7—7 of Figure 6; and

Figure 8 is a sectional view of a valve illustrating still another form of my invention.

In Figures 1 and 2 of the drawings a conventional type of soda fountain draft arm 10 is shown as being provided to deliver a carbonated liquid such as a carbonated water or any other form of carbonated beverage, the operation of which is controlled by means of a valve operating handle 11 in a well known manner. A delivery valve 12 constructed in accordance with my invention is secured to the lower end of said draft arm, as will hereinafter more clearly appear as this specification proceeds, and is enclosed by a casing 13 threaded on the lower end of said draft arm and opening at its bottom, to form a spout for the discharge of the carbonated liquid.

The delivery valve 12 is herein shown as having a central upright member 14 threaded in an apertured portion 15 of the draft arm 10. Said central member has a central fluid passageway 16 with a restricted discharge nozzle. Said fluid passageway communicates with a central passageway 17 of said draft arm, for delivering a fine stream of carbonated water when the valve handle 11 is turned to one position, which stream of water is required for certain soda fountain products.

A valve casing 18 extends along and encircles the central member 14 and is spaced therefrom and is secured thereto in abutting relation with respect to the lower end of said draft arm by means of a nut 19 threaded on the lower end of the upright member 14, and abutting the bottom of said casing.

The casing 18 has an upper chamber 21 open at its upper end and communicating with a plurality of passageways 22, 22 formed in said draft arm, for delivering carbonated fluid from said draft arm to the delivery valve 12. Said chamber is formed from an annular member 23 having a downwardly extending flanged portion 24, which is secured at its lower end to a spacing member

25 of a substantially cylindrical construction. Holes 26, 26 are drilled through said spacing member, parallel to its vertical axis, and form fluid passageways leading to a chamber 27 having a valve disk 30 of a double valve 31 movable therein. Said valve disk is adapted to restrict an

opening 32 leading from said chamber to radial passageways 33, 33 formed in said spacing member. Said passageways 33, 33 lead from said opening 32 to the inside of the casing 13, for discharging carbonated liquid to the atmosphere through the spout formed in the lower end of said casing.

The chamber 27 is formed from a cylindrical member 35, secured to the lower end of the spacing member 25, as by welding, and depending therefrom. An annular disk 36 is threaded in the lower end of said cylindrical member and has a cylindrical bottom member 37 abutting its lower end and mounted on the lower end of the upright central member 14 and held in position thereon by means of the nut 19. Said cylindrical bottom member with its closed lower end forms a chamber 39 communicating with the chamber 27 and having a valve disk 40 of the double valve 31 movable therein to open or restrict an annular passageway 41 encircling the stem of said valve and connecting said chambers together.

Passageways 42, 42 lead from the chamber 39 to the inside of the casing 13. Said passageways are of a relatively small diameter in comparison with diameters of the passageways 33, 33 and are arranged to provide a predetermined back pressure in the chamber 39, which is sufficient to raise the double valve 31 above the bottom of the chamber 39, and to support the weight of said double valve.

When the valve handle 11 of the draft arm 10 is turned to admit carbonated fluid through the passageways 22, 22, carbonated fluid will flow through said passageways to the chamber 21 and through the holes 26, 26 in the spacing member 25, to the chambers 27 and 39. The double valve 31 being balanced, the carbonated fluid will exert equal pressures in opposite directions on the facing sides of the disks 30 and 40. The distance between said disks is such that the disk 30 will seat on the bottom of the spacing member 25, to restrict or close the opening 32 formed therein and the disk 40 will seat on the bottom of the disk 36, to restrict or close the passageway from the chamber 39 to the chamber 27. The restricted passageways 42, 42 leading from the chamber 39 will set up a pressure in said chamber and will provide a back pressure on the disk 40 which will tend to raise said double valve and restrict the opening 32 leading to the passageways 33, 33, to cause the carbonated beverage to pass into said opening in the form of a thin circular film and pass to the atmosphere through the passageways 33, 33 and the spout formed by the bottom of the casing 13.

When the flow of carbonated fluid is turned off, the double valve 31 will drop of its own weight until the lower end of the stem of said valve rests on the bottom of the chamber 39, as is shown in Figure 2. This will allow any sediment which may have become lodged between the valves and their seats to clear itself from said valves and pass on through the valve.

It should here be noted that when the carbonated water is flowing through the valve, the passageways 42, 42 are so proportioned that the rate of flow of the water through said passageways will be such as to provide enough back pressure to act on the bottom of the disk 40 of the double valve 31, to raise said double valve from its wide open position and to support the weight of said double valve. It is also apparent that the diameter of the holes forming said passageways 42, 42 determines the equilibrium position of said double

valve, assuming that the resistance offered by the passageways 33, 33 is negligible in comparison with the resistance offered by the passageways 42, 42. Thus when the size of the passageways 42, 42 is properly determined and fixed, a valve is provided which has constant flow characteristics regardless of variations in pressure of the source of carbonated fluid.

In the modified form of my invention shown in Figure 5 a chamber 43 is mounted in a valve casing 44 on the end of a pipe 45. Said pipe is connected with a source of carbonated fluid and communicates with the inside of said chamber. A limp diaphragm 46 is connected between a top cover 47 for said casing and an upper flanged portion 49 of said casing. An opening 48 is provided in the top of said cover, to relieve said diaphragm from air pressure during compression thereof. A stem 50 of a double valve 51 is mounted on and depends from said diaphragm through the chamber 43. A valve disk 52 is threaded on said stem within said chamber and is adapted to restrict the passage of fluid through an opening 54 in the central portion of an annular member 53, which forms the top of said chamber. A valve disk 55 is threaded on the lower end of said valve and is adapted to restrict the passage of fluid through an opening 56 in a bottom portion 57 of said chamber. Said valve stem is also slidably guided at its lower end in a disk 59, closing the lower portion of the casing 44. A plurality of restricted passageways 60, 60 extend through said disk for the passage of carbonated fluid therethrough and through a spout 61, threaded on the lower end of said valve casing and depending therefrom.

When carbonated fluid flows through the pipe 45 into the chamber 43 and out of the openings 54 and 56 formed in the top and bottom of said chamber, the restricted passageways 60, 60 will set up a pressure within the casing 44, which will act on the diaphragm 46. This will cause said diaphragm to raise the double valve 51, to restrict the flow of carbonated fluid through the openings 54 and 56 and cause the fluid to pass through said openings in the form of thin circular films. It should here be understood that said double valve will be raised by said diaphragm until an equilibrium position will be reached which is determined by the size of the passageways 60, 60. When this equilibrium position has been reached, the rate of flow of the carbonated fluid will be such as to establish a pressure in the casing 44, which is sufficient to support the weight of said double valve.

In the form of my invention shown in Figures 6 and 7, a valve 60 is secured to and depends from a conventional type of draft arm in much the same manner the valve 12 is secured to the lower end of the draft arm 10. In this form of my invention, carbonated fluid enters a chamber 61 at the upper end of said valve and passes downwardly through a plurality of vertically extending passageways 63, 63 formed in an intermediate member 64 of said valve, which lead through said intermediate member into an annular chamber 65. Said annular chamber is formed by a member 66 threaded in the lower end of the intermediate member 64. Said member 66 encircles and is spaced from the stem of a double valve 67. Said double valve has a valve disk 69 on its upper end, movable in a chamber 70 in the lower end of said intermediate member. Said chamber communicates with a plurality of radial passageways 72, 72 disposed above said

chamber and leading to the outside of said valve into a casing 73. Said valve disk is adapted to restrict the passageway from said chamber to said radial passageways and to deliver the fluid to said passageways in the form of a thin film. Said casing is similar to the casing 13 shown in Figure 1 and is threaded on and depends from an annular flanged member 68, which is threaded on the upper end of the intermediate member 64 and abuts the bottom of the draft arm. A spout 74 is formed at the lower end of said casing, for the discharge of carbonated fluid.

A plurality of apertures 75, 75 lead through the member 66 from the chamber 65 to the chamber 70, just beneath the disk 69 of the double valve 67, and are so arranged that jets of carbonated fluid passing therethrough will exert a direct pressure on said valve disk to move said valve upwardly into position to restrict the passage of carbonated fluid from said chamber 70 to the passageways 72, 72 and form a thin orifice to cause the carbonated fluid to pass to said passageways in the form of a thin circular film. Carbonated fluid will also pass in the space between said member and the stem of the valve 67 into a chamber 71 disposed beneath said member 66. Said chamber 71 is held in abutting relation with respect to the bottom of the member 66 by means of a nut 79 threaded on the lower end of a central upright member 80 of said valve, which is similar to the upright central member 14 of the valve 12.

The chamber 71 has a lower disk 81 of the double valve 67 movable therein, to restrict the passageway leading from said chamber to the chamber 70. A plurality of restricted passageways 83, 83 lead from said chamber 71 to the inside of the casing 73, to cause a pressure to be built up in said chamber, which will tend to move said double valve vertically and hold it in equilibrium in much the same manner as in the form of my invention shown in Figure 2.

It may here be seen that in the embodiment of my invention just described, the jets of carbonated fluid entering the chamber 70 directed upwardly against the underside of the valve disk 69 will lift said valve disk with the first surge of carbonated water, and will bring said valve into position where the back pressure thereon will become effective to hold it in this elevated position.

In the form of my invention shown in Figure 8, a chamber 85 is shown as being supported within a valve casing 86 on a pipe 87, which is adapted to supply carbonated fluid to said chamber in much the same manner as in the form of my invention shown in Figure 5. Said chamber is of a substantially cylindrical form with an annular top 88 and an annular bottom 89. The opening in said annular top is adapted to be restricted by a valve disk 90 mounted within said chamber on the upper end of a hollow valve stem 91. Said valve stem is slidably mounted on a rod 92, which extends through and is secured to the top of the casing 86, by means of a nut 93 threaded on the upper end of said rod and abutting the top of said valve casing. A nut 94 threaded on the lower end of said rod limits downward movement of said valve along said rod. A valve disk 95 is mounted adjacent the lower end of said valve stem and is adapted to restrict the opening in the bottom of said chamber. Said valve disk is of a larger diameter than the valve disk 90, but the portion of said valve disk exposed directly to pressure in

said chamber is of substantially the same area as the corresponding portion of the valve disk 90, to balance said valve.

When carbonated fluid enters the chamber 85 through the pipe 87, the pressure between the upper surface of the valve disk 95 and the bottom 89 of said chamber will be reduced below the pressure in the valve casing 86 by the rapid flow of the carbonated fluid between these two surfaces. This will produce a suction which will cause the valve disk 95 to move towards the bottom 89 of said chamber and move the valve disk 90 upwardly to form a thin orifice which will restrict the flow of carbonated fluid from the upper end of said chamber and cause it to flow into the casing 86 in the form of a thin film. The orifice between the valve disk 95 and bottom of the chamber 85 will likewise be restricted to deliver carbonated fluid in the form of a thin film. When the flow of carbonated fluid through the pipe 87 stops, the valve disks 90 and 95 will drop to a wide open position to permit sediment to wash through the valve.

While I have herein shown and described several forms in which my invention may be embodied, it will be understood that the construction thereof and the arrangement of the various parts may be altered without departing from the spirit and scope thereof. Furthermore, I do not wish to be construed as limiting my invention to the specific embodiments illustrated, excepting as it may be limited in the appended claims.

I claim as my invention:

1. In a delivery means for carbonated fluid, a chamber, a substantially unrestricted passageway leading from one wall of said chamber, another chamber, an unrestricted passageway connecting said chambers together and passing through an opposite wall of said first mentioned chamber from said one wall, a double valve having a valve member in each of said chambers and each cooperating with an unrestricted passageway leading from the respective chamber and the walls through which said passageways extend to form thin delivery spaces, delivering the carbonated fluid through said passageways in the form of thin film-like sprays, said second mentioned chamber having a restricted passageway leading therefrom, to build up pressure in said second mentioned chamber to act on said valve in said second mentioned chamber and move said valves toward the walls through which said passageways extend, and conduit means delivering carbonated fluid to said first mentioned chamber.
2. A delivery means for carbonated fluid in accordance with claim 1 wherein the conduit means comprises passageways arranged to direct jets of carbonated fluid on the bottom of the valve member in the first mentioned chamber.
3. In a delivery means for carbonated fluids, a chamber having two vertically spaced horizontal walls, a passageway leading from one of said walls, a pipe delivering carbonated fluid to said chamber, another chamber disposed beneath said first chamber, a passageway leading from the other of said walls and connecting said chambers together, a valve member in each of said chambers and cooperating with said passageways to restrict the passage of carbonated water therethrough, means connecting said valve members to move together to wide open positions by gravity, and said second mentioned chamber having a restricted passageway leading therefrom and so proportioned with respect to said other passageways as to set up a predetermined back

pressure in said second chamber to act on said valve member in said second chamber and move said valve members upwardly toward said horizontal walls and the passageways therethrough and to cooperate therewith and form thin flow spaces for the carbonated fluid, forming the carbonated fluid into thin film-like sprays.

4. A delivery means for carbonated fluids including two vertically aligned chambers, means for delivering carbonated fluid to the upper of said chambers, a substantially unrestricted passageway leading from an upper wall of said upper chamber, a substantially unrestricted passageway leading through an upper wall of the lowermost of said chambers and connecting said chambers together, a restricted passageway leading from the lowermost of said chambers and so proportioned with respect to said last mentioned unrestricted passageway as to build up pressure in said lowermost chamber, a separate valve member in each of said chambers, means connecting said valve members to move together, said valve member in said lowermost chamber being acted upon by the pressure of carbonated fluid built up therein, and move said valve members against gravity toward the unrestricted passageways leading through the walls of said chambers, and said valve member in said upper chamber being of a larger cross sectional area than said passageway through the upper wall thereof, to form with said wall a thin delivery space to deliver carbonated fluid through said passageway to a region of low pressure in the form of a thin film-like spray when said valve member is moving against gravity.

5. A delivery means for carbonated liquids including two vertically aligned chambers, means for delivering carbonated fluid to the upper of said chambers, a substantially unrestricted passageway leading from an upper wall of said upper chamber, a substantially unrestricted passageway leading through an upper wall of the other of said chambers and connecting said chambers together, a valve disk in each of said chambers of a larger cross sectional area than said passageways and cooperating therewith, a stem connecting said valve disks to operate together, a restricted passageway leading from the lower of said chambers and so proportioned with respect to said unrestricted passageways as to build up pressure in said upper chamber to move said valve disks against gravity toward said walls, and with said walls and passageways form thin delivery spaces to deliver the carbonated fluid to a region of low pressure in the form of a thin film-like spray.

6. In a delivery means for carbonated fluid, a valve chamber, means for supplying carbonated fluid to said valve chamber, said valve chamber having annular top and bottom surfaces for the discharge of carbonated fluid therefrom through the open portions of said annular surfaces, a second valve chamber mounted beneath said valve chamber and adapted to receive carbonated fluid discharged through the annular bottom surface of said first valve chamber, a balanced double valve having a valve disk mounted within said first mentioned chamber and movable into position to form a thin orifice between the top of said valve disk and the bottom of said top annular surface of said chamber to deliver carbonated fluid through the open portion of said annular surface in the form of a thin film-like spray, a valve stem depending from said valve disk into said second valve chamber and having

another valve disk mounted thereon in said second chamber and movable into position to form a thin orifice between the bottom of said bottom annular surface and the top of said valve disk to deliver carbonated fluid into said second chamber through the open portion of said annular surface in the form of a thin film-like spray, and said second valve chamber having a plurality of restricted passageways therein for the discharge of carbonated fluid therethrough, said passageways being so proportioned as to restrict the passage of carbonated fluid therefrom and to build up a back pressure therein, to act on said lower valve disk and move said valve disks into positions to form said thin orifices, said valve disks moving downwardly to wide open positions when the flow of carbonated fluid into said chambers stops.

7. In a delivery means for carbonated fluid, a valve chamber having annular top and bottom surfaces for the discharge of carbonated fluid therefrom through the open portions of said annular surfaces, a second valve chamber mounted beneath said first valve chamber and adapted to receive carbonated fluid discharged through the annular bottom surface of said first valve chamber, said second valve chamber having a plurality of restricted passageways therein for the discharge of carbonated fluid therethrough, and said passageways being so proportioned as to restrict the passage of carbonated fluid therefrom and to build up a pressure in said second chamber, a balanced double valve having a valve disk mounted within said first mentioned chamber and movable into position to form a thin orifice between the top of said valve disk and the bottom of said top annular surface of said chamber to deliver carbonated fluid through the open portion of said annular surface in the form of a thin film-like spray, a valve stem depending from said valve disk into said second valve chamber and having another valve disk mounted thereon in said second chamber and movable into position to form a thin orifice between the bottom of said bottom annular surface and the top of said valve disk to deliver carbonated fluid through the open portion of said annular surface in the form of a thin film-like spray, to cause the carbonated fluid to build up a predetermined back pressure therein, and passageways for the carbonated fluid leading into said first chamber and arranged to direct jets of carbonated fluid on the bottom of said upper valve disk, to initially move said double valve into position to form said thin orifices leading out of said first valve chamber, the back pressure on said lower valve disk in said second chamber serving to hold said valves in said predetermined position, and said valve disks moving to a wide open position to permit said valves to clean themselves when the flow of carbonated fluid into said chambers stops.
